Primary Examiner—Melody N. Brown
Attorney, Agent, or Firm—Leon E. Redman; Malcolm L. Sutherland**[57] CLAIM**

The ornamental design for a hitch mountable bicycle carrier with tail lights, as shown and described.

DESCRIPTION

FIG. 1 is a perspective view of a hitch mountable bicycle carrier with tail lights showing our new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof;

FIG. 7 is a front elevational view thereof; and,

FIG. 8 is a perspective view of a second embodiment of a hitch mountable bicycle carrier with tail lights showing our new design having round tail lights, all other views of the design are substantially similar in appearance as in FIGS. 2-7.

1 Claim, 4 Drawing Sheets Fig. 1.

Fig. 2.
